WILLIAM H. CLIFF, OF TERRE HAUTE, INDIANA, ASSIGNOR OF AN UNDIVIDED INTEREST TO TERRE HAUTE BOILER WORKS COMPANY, OF TERRE HAUTE, INDIANA, A CORPORATION OF INDIANA

CASING FOR BOILERS

Application filed December 19, 1928. Serial No. 326,998.

My invention relates to improvements in boilers and particularly to inclosing casings for boilers.

It is generally designed for use in connection with sectional boilers, which as a rule are substantially rectangular in shape.

It is one of the objects of my invention to provide an inclosing casing for boilers, which will give a finished and an attractive appearance to the boilers, and which at the same time will provide an insulating cover for the boiler to confine the heat thereof and prevent wasteful dissipation of the heat.

For the purpose of disclosing my invention, I have illustrated one embodiment thereof of the accompanying drawings, in which:

Fig. 1 is a side elevation of a boiler embodying my invention, the (sectional) casing being shown partly in section; Fig. 2 is a front elevation thereof, showing the casing partly in section; Fig. 3 is a plan view of the casing; Fig. 4 is a transverse section of the top of the casing; Fig. 5 is a detailed section 25 on the line 5—5 of Fig. 2. Fig. 6 is a detailed section on the line 6—6 of Fig. 1; Fig. 7 is an elevation of the front panel of the casing; Fig. 8 is an elevation of a side panel of the casing; Fig. 9 is an elevation 30 of the rear panel of the casing; Fig. 10 is a sectional view on the line 10—10 of Fig. 3; Fig. 11 is a sectional view on the line 11—11 of Fig. 3; Fig. 12 is a sectional view on the line 12—12 of Fig. 7; Fig. 13 is a sectional view on the line 13—13 of Fig. 8; Fig. 14 is a detailed elevation of one corner of the side panel; Fig. 15 is a sectional view on the line 15—15 of Fig. 8; Fig. 16 is a detailed sectional view on the line 16—16 of Fig. 8, and 35 Fig. 17 is a detailed sectional view on the line 17—17 of Fig. 9.

In the embodiment illustrated, the casing comprises two side panels 1, a front panel 2, a rear panel 3, and a top 4.

The side panels may be one continuous sheet or may be formed of a plurality of sheets, the adjacent edges of which are in-turned to form angularly disposed flanges 5, secured together at suitable intervals along 45 their lengths by bolts 6 so that, the panel is

in effect one complete panel, although formed of a plurality of sections. The material at the top and two side edges of the panel is bent back upon itself as at 7 and then at right angles to form a flange 8 at the top and on the two side edges of the panel. Within this flange, which extends around the edges, except at the bottom thereof, is mounted a suitable insulating material 9, which may be in the form of asbestos or 55 any other desirable heat insulating material.

The front and rear plates at each edge, are bent backwardly to form the right angle lip 10 and on each of the side edges of the front and rear plates and are secured preferably by spot welding, an angle member 11, one leg 12 of which extends parallel with, but is spaced apart from the flange 10. These front and back members are provided with suitable openings therein to accommodate 60 the fire doors, cleanout doors and smoke-boxes and the like, and if desired, these sections may be split as illustrated in Fig. 9 so that, the parts may pass over the projections and then connect together by 65 bolts 13, which pass through inturned flange 14.

The top panel is formed of two sections of sheet metal 15 and 16, these sections being adapted to overlap along the center line 70 and to this end the metal of the section 15 is turned back upon itself as at 17 and then inwardly to form an angled flange 18 and the material of the opposite section 16 is turned down as at 19 to form an abutting flange. 75 Each section has secured on each edge angle bars which are secured in position preferably by spot welding, and one leg 20 of the bars extends parallel with, but is spaced apart from an inturned flange 21 of the top. 80 Suitable openings 22 are formed in the abutting sections at the top to accommodate steam pipes or the like.

The underfaces of the two top sections are 85 lined with suitable insulating material in a manner similar to the two side panels.

In assembling the parts in position, the two side panels are placed against the sides of the boiler. It will be noted that these two side panels are provided at their bottoms 100

with angles 23, which at the forward and rear edges are turned to extend parallel with the front and rear of the boiler as at 24.

After the two side members have been positioned, the front member is slipped over the front edges of the two side members and drops downwardly in position. This causes the bottom edge of the front member to engage behind the upturned leg 25 of the front portion of the angle members 23 so that, it will be locked against longitudinal displacement. The front edges of the two side members take into the space between the flange 10 and the legs 12 of the angle members and are thus locked against transverse displacement. The rear member is similarly placed in position. Thus interlocking the parts thus far assembled so that, the side members are prevented against displacement and the end members, at least, their bottoms are locked against displacement with respect to their side members. After the sides and ends are assembled, the two top sections are placed in position so that, the upper edges of the sides and end sections take into the space between the angle legs 20 and inturned flange 21, thereby securely interlocking all of the parts together and forming a rigid self-supporting, self-locking, inclosing casing, which may be assembled without the use of interlocking bolts, and which will remain in position so long as necessary, but which may be disassembled and removed from the boiler without the use of tools of any kind.

I claim as my invention:

1. A boiler casing comprising side panels and end panels, said side panels having at their bottom corners inturned end members provided with upwardly projecting flanges extending at right angles to the side panels and said end panels having at their edges a pair of spaced apart flanges adapted to embrace the edges of the side panels to prevent lateral displacement thereof, the bottom edges of said end panels being constructed to be embraced by said upturned flanges on the side panels to prevent relatively displacement between the panels longitudinally.

50 2. A boiler casing comprising side and end panels, the end panels having inturned spaced apart flanges, adapted to embrace the edges of the side panels to prevent lateral displacement thereof, means on the bottom edges of the side panels and extending at right angles to said panels embracing the bottom edges of the end panels to prevent longitudinal displacement of the end panels and a cover member having means for interlocking with the upper edges of the end panels, for preventing longitudinal displacement of the upper portion of the end panels.

65 3. A boiler casing comprising side panels having secured thereto at their lower corner edges angle irons, said irons being inturned at

the front and rear ends of the panels, end panels having inturned flanges at its edges and having secured thereto angle irons, one leg of the irons being adapted to extend parallel with, but spaced apart from the inturned flange, and a cover member having its edges turned down to form downwardly extending flanges and having secured to its edges angle irons having one leg parallel with said down-turned flange and spaced apart therefrom, 75 said end panels being adapted, when assembled to engage at their lower edges behind the upwardly extending legs of the inturned ends of the angle bars, secured at the lower edges of the side panels, the edges of said 80 side panels being adapted to engage between the angle bars and flanges on the end panels and the top edges of the side and end panels being adapted to fit between the flanges and angle bars on the cover member, whereby all 85 of said parts are interlocked into a rigid structure.

4. A boiler casing comprising side and end panels, the end panels having inturned spaced apart flanges at their edges adapted to embrace the edges of the side panels to prevent lateral displacement thereof, and a cover member including a pair of sections, each having downwardly extending spaced apart flanges at its outer edges adapted to embrace 95 the upper edges of the end and side panels.

In witness whereof I, WILLIAM H. CLIFF, have hereunto set my hand at Terre Haute, Indiana, this 30th day of November, A. D. one thousand nine hundred and twenty eight. 100

WILLIAM H. CLIFF.
